ATTORNEY

UNITED STATES PATENT OFFICE

STUART GRAYSON GARRETT, OF TULSA, OKLAHOMA

CHOKE CONTROL FOR CARBURETORS

Application filed January 19, 1927. Serial No. 162,157.

This invention relates to choke controls for carburetors and is more particularly directed to the type of device described and claimed in my co-pending application, Serial No. 5 137,303, filed September 23, 1926, now Patent 5 #1,616,083.

An object of the invention is the provision of a device as is adapted to engage the usual actuating rod for the choke valve of an internal combustion engine which will permit readily actuation of the choke valve but which will cause the rod to travel slowly after release as the valve is opened by the usual spring.

15 A further object of the invention is the provision of a device associated with the actuating rod for a choke valve and supported from the dash of an automobile which will prevent the choke valve from readily opening means 20 being included in the device for timing the opening of the choke valve.

This invention will be best understood from a consideration of the following detailed description, in view of the accompanying drawings forming a part of the specification; nevertheless, it is to be understood that the invention is not confined to the disclosure, being susceptible of such changes and modifications as shall define no material departure 25 from the salient features of the invention as 30 expressed in the appended claims.

Figure 1 is a side view in elevation of a form of the invention.

Figure 2 is a modified form of the invention, and

Figure 3 is a further modified form of the control means.

Referring more particularly to the drawings, various forms of controlling means are shown which are operated through a plunger and air pressure, air being drawn into a cylinder so that when the spring tends to return the rod to its normal inoperative position air must be forced out by the action of a piston through a restricted opening in the cylinder carrying said piston.

Referring more particularly to Figure 1 a dash 50 provides a bearing for a reciprocating rod 51 which is adapted to actuate the choke valve. A piston rod 52 has a bent end

53, connected at 54, to the rod 51. The other end of the rod is connected to a piston 55 in a cylinder 56. 57 is a guide for the choke rod. The outer end of the cylinder, as shown at 58, is secured to a vertical partition 59 of 55 the automobile.

A pipe 60 has one end 61 connected to the outer end of the cylinder 56 and its other end connected with a valve casing 62 carried by the dash 50. A valve stem 63 is connected to the valve in the casing 62 and is adapted to actuate the valve to permit a predetermined degree of flow of air from the cylinder 56 through a short conduit 64. By properly manipulating the valve stem 63 the discharge 65 of air through the pipe 64 may be readily controlled in order to time the movement of the piston 55 when the rod 51 is actuated for opening the choke valve through the action of the spring 15.

Referring to Fig. 2 a similar form of control mechanism is shown in which a rod 65 is mounted for reciprocation in a bearing 66 and through a passage 67 in the dash 68. A finger piece 69^a is employed for reciprocating the rod.

A cylinder 69 is carried by a bracket 71 having means 72 for adjusting the inner end of the cylinder 69, the bracket being secured, as shown at 73, to a lateral flange 74 of the dash 68.

A piston 75 is mounted for movement in the cylinder 69 and is connected to a rod 76 having a bent portion 77 connected at 78 to the rod 65.

The outer end of the cylinder 69 is connected with a conduit 79 which in turn carries a valve casing 80 in which is mounted a valve adapted to be operated by a valve stem 81. A discharge pipe 82 is connected with the casing 80. When the rod 65 is moved in the direction indicated by the arrow in Fig. 7 the piston 75 draws in air through the conduit 82 or a check valve connected to the discharge end of the cylinder and when said rod is released and the choke valve is being opened the piston 75 must act against the air in the cylinder 69, the discharge of the air from pipe 82 being controlled by the valve in the casing 80 so that the timing of the re-

turn reciprocating movement of the rod 65 may be controlled at will.

A simplified form of the invention shown in Figs. 1 and 2 is illustrated in Fig. 3 in which a cap is threaded onto an end of the cylinder 91. A plug 94 is threaded into the cap 90. A flange 92 screwed tight against instrument board 93 holds the cylinder in place.

10 The plug is adapted to provide a bearing for a reciprocating rod 95. A piston 96 is mounted for movement in a cylinder 91 and is adapted to draw air through the conduit 97 and a valve 98 actuated by a threaded valve 15 stem 99 operated through a finger piece 100 is adapted to control the discharge of air from the outer end of the cylinder when the rod 95 has been released to permit opening of the choke valve 14 through the actuation 20 of the spring 15. The rod 95 has a reduced portion 101 extending through a packing gland 102 and a threaded nipple 103. The reduced portion 101 is adapted to be connected directly to an arm 20 of the bell crank 25 lever 19, as shown in Figures 1 and 2.

I claim:—

1. A choke control for carburetors comprising a slidably mounted rod, a choke valve, spring means for moving the valve to open position, a cylinder having an air vent for the admission and discharge of air, a piston slidably mounted in the cylinder, a piston rod having an arm bent at an angle to said rod, the bent arm being connected at its free 35 end to the choke rod, whereby reciprocation of the piston will inhale air into the cylinder when the choke valve is moved to closed position, said spring means tending to open the valve against the action of the piston on the air in the cylinder so that the rod will 40 be slowly reciprocated for opening the choke valve.

2. A choke control for carburetors comprising a slidably mounted rod, a choke valve, 45 spring means for moving the valve to open position, a cylinder having an air vent for the admission and discharge of air, a piston slidably mounted in the cylinder, a piston rod having an arm bent at an angle to said rod, the bent arm being connected at its free 50 end to the choke rod, whereby reciprocation of the piston will inhale air into the cylinder when the choke valve is moved to closed position, said spring means tending to open 55 the valve against the action of the piston on the air in the cylinder so that the rod will be slowly reciprocated for opening the choke valve, and means for controlling the discharge of air from the cylinder for regulating 60 the rate of movement of the rod.

STUART GRAYSON GARRETT.
